CLAIM

The ornamental design for a combined fluorescent lantern and remote control, therefor, as shown and described.

DESCRIPTION

FIG. 1 is front elevational view of the combined fluorescent lantern and remote control therefor showing our new design;

FIG. 2 is a front perspective view thereof;

FIG. 3 is a top plan view thereof;

FIG. 4 is a bottom plan view thereof; and,

FIG. 5 is a side elevational view thereof.

The rear surface of the remote control is flat and plain.

FIG.2

FIG.5
